UNITED STATES PATENT OFFICE.

LOUIS CHARLES REESE, OF SAGINAW, MICHIGAN.

CHARGING AND DISCHARGING OF AUTOMATIC OVENS, PROOFING-CHAMBERS, AND THE LIKE.

1,220,457.

Specification of Letters Patent. Patented Mar. 27, 1917.

Application filed February 28, 1916. Serial No. 81,009.

To all whom it may concern:

Be it known that I, LOUIS CHARLES REESE, residing at Saginaw, in the county of Saginaw and State of Michigan, have invented 5 new and useful Improvements in the Charging and Discharging of Automatic Ovens, Proofing-Chambers, and the like, of which the following is a specification.

This invention relates to automatic baking 10 ovens, proofing chambers and like apparatus through which the articles to be subjected to the process worked therein, are passed in a certain predetermined time and in a circuitous—partly horizontal, partly more or 15 less vertical—route by endless chains, and consists in novel means of charging and discharging these apparatus.

The object of this invention is to perform 20 these operations automatically and without stopping the apparatus, in a most simple, effective and economic manner.

To this end, I place the articles to be treated or the containers holding them, on 25 trays which may also be formed by joining rows of these containers by suitable means as iron bands, and suspend these trays from the chains carrying them through the apparatus, by easily connected and disconnected devices, consisting of crossrods rotatably 30 mounted at both ends in the links of the chains or in blocks or the like attached thereto, and carrying rotatably mounted hangers provided with brackets, and of studs fixed to the trays and adapted easily and automatically to engage with and disengage from 35 the said brackets.

The loaded trays are conveyed into the apparatus by automatic means, usually an ordinary endless-band-conveyer, to a point 40 so determined and arranged that the brackets of the hangers suspended from the crossrods of the chains, while passing upward in close proximity to the tray on the conveyer, are bound to engage with the studs fixed to 45 the tray, and thus the tray will be picked up from the conveyer, lifted upward and then carried through the apparatus.

The trays are discharged from the latter 50 by depositing them on their downward passage on automatic means for carrying them away, usually an endless-band-conveyer, passing underneath at a point so determined and arranged that the studs fixed to the tray are bound to disconnect themselves from the 55 brackets of the hangers suspended from the

crossrods of the chains while traveling downward, whereupon the latter with their appurtenances and the disconnected trays are quickly removed in different directions, the conveyer taking away the trays, being so 60 constructed and traveling with such velocity that they cannot interfere with the chains, their crossrods, hangers or the brackets attached thereto. As the charging and discharging points of the apparatus preferably 65 sprocketwheels are installed for the chains to run over in order to give to the latter, to the suspending devices and to the trays, just picked up or to be disconnected, ample stability and the proper direction. 70

The feeding devices used hitherto for this kind of apparatus made it necessary that the chains were stopped while the trays were charged and discharged, and the unavoidable consequences were jerks and shocks 75 liable greatly to damage the more or less soft goods in appearance, shape and size. This was especially the case in automatic baking ovens of this class. 80

The accompanying drawings, which serve 85 for more fully explaining the novel features and devices and the working of the invention, show its application to a proofing and baking apparatus used for hearth bread, buns, crackers or the like. 85

Figure 1 is a side elevation of a tray, showing the construction of the brackets, of the hangers and of the crossrods carrying the latter, and the working together of the brackets and the studs fixed to the tray. 90

Fig. 2 represents a longitudinal section of a tray showing the same bracket and stud arrangement as Fig. 1, the connection to the chains and the wheel-supports of the crossrods. 95

Fig. 3 represents an arrangement for transferring trays provided with the same suspending devices as shown in Fig. 1 and Fig. 2, from a proofing chamber to an oven, and Fig. 4 an arrangement for discharging 100 the trays from the latter.

Fig. 5 shows a vertical cross section of a tray resting on a conveyer, and the position of the brackets and the hangers carrying them, in regard to the tray and the conveyer. 105

In Fig. 1, Fig. 2 and Fig. 5, A represents a tray consisting of the bottomplate a and the side pieces a_1 arranged at the longer sides and a_2 at the narrower sides of the 110

tray, forming the framework of the tray. The side pieces a_2 are strengthened and widened by the half circular projections a_3 in order to carry the studs B and B_1 which 5 engage with the curved, hollow-hand like projections or brackets c and c_1 of the hangers C and C_1 . The latter consist of the branch parts c_2 and c_3 , the crossbar c_4 and the annular block c_5 , the circular opening 10 of which is loosely fitted over the crossrod D connecting the chains H and H_1 . The blocks c_5 are kept in position on the crossrod D by means of the set-collars c_6 and c_7 and turn so easily around D that the tray A 15 suspended by its studs B and B_1 engaging with the brackets c and c_1 of the hangers C and C_1 , from the crossrod D , is always kept in an horizontal position, when the latter is turned during its circuitous course 20 through the apparatus.

The crossrod D rests near to, but outside the hangers C and C_1 , on the loose wheels E and E_1 , which revolve freely around D and run in the grooves f for E and f_1 for E_1 25 of the rails F and F_1 . The latter are supported by the brackets G and G_1 fixed to the walls or structure of the apparatus.

The rails F and F_1 carry in this way the crossrod D and with it the chains H and H_1 30 and the tray A , while these chains travel more or less horizontally. When the direction of the chains is altered more or less to the vertical, or from the latter to the horizontal again, the crossrods, wheels and trays 35 are carried by the chains H and H_1 running over and supported by the teeth of sprocket-wheels in the well known manner of apparatus of this kind.

In Fig. 3, O represents diagrammatically 40 the sprocketwheel around which the chains H travel inside an oven before its charging opening, and P the sprocketwheel for the chains H before the discharging opening in a proofing chamber situated alongside the oven. The sprocketwheel O revolves around the axle o , and the sprocketwheel P around the axle p , both moving in the same direction as shown by the arrows. I is an horizontal endless-hand-conveyer driven by the 45 rollers K and K_1 rotated around the axles k and k_1 in the direction of the arrows by suitable driving means, the carrying surface of the conveyer traveling from the proofing chamber toward the oven. The roller K is 50 arranged within the proofing chamber well underneath the sprocketwheel P , and the roller K_1 within the oven underneath the sprocketwheel O . Adjacent to the roller K_1 , and still farther in the charging opening 55 of the oven, a rest is preferably arranged for the trays arriving there; it consists of the parallel, loose rollers L , L turning easily around their axles l , l supported by the bracket like staging M . The carrying plane 60 of the rollers, L , L is slightly inclined from

the conveyer I in a downward direction so that the trays arriving there from the latter easily slip down against the crossplate N and thus attain the correct position for the studs of the trays A to slip into the brackets 70 of the hangers traveling upward. The conveyers I (Fig. 3 and Fig. 5) and L , as in fact every conveyer used in this arrangement for charging and discharging trays, must not be wider than the trays carried by 75 the same, and so arranged in the apparatus they serve, that the brackets c and c_1 of the hangers C and C_1 , while passing by, can not interfere with the conveyer or the trays thereon. In order to secure for the trays 80 the right position on the conveyer, the latter may be made of the same width as the trays are long, and provided at the sides of the traveling band with studs i for the trays to fit between. 85

In the proofing chamber the chains H carrying the trays containing the fully proofed dough pieces ready for the oven, travel at first vertically downward and then around the sprocketwheel P where the trays are deposited on the conveyer I , whereupon the chains take the crossrods with their empty hangers to the charging place of the proofing chamber to be reloaded with fresh trays. 90

When in its downward passage in the 95 proofing chamber, the tray A_1 reached the position I of its hanger C_1 and crossrod D_1 , the preceding tray A_2 with its hanger C_2 and crossrod D_2 has just attained the position II and is being dropped on the conveyer I , and the crossrod D_3 with the empty hanger C_3 has reached the position III . 100

The tray A_3 which, while in the proofing chamber, had been attached to the hangers C_3 carried by the crossbar D_3 , has at the 105 same time reached the position I in the oven, and resting on the roller platform L , against the support N , is just being picked up by the brackets of the hangers C_2 of the crossrod D_2 engaging the studs B_3 of the tray. 110 The tray A_4 which entered the oven previously to the tray A_3 , has been lifted with its hangers C_3 and crossrod D_3 by the chain H traveling upward onto the position II in the oven, while the crossrod D_1 with its 115 empty hangers C_1 is moving toward the platform L , ready to pick up and lift the tray A_2 as soon as it has arrived from the proofing chamber in the position I on the platform L in the oven. 120

This cycle of operations is repeated continuously. For the exact working of the arrangement, it is—of course—essential that the conveyer I travels with the correct speed for the trays coming from the proofing 125 chamber to be picked up by the crossrods in the oven, a result which can easily be attained by well known means. While Fig. 3 shows the discharging arrangement in which the conveyer carrying away the trays, 130

travels at once in opposite direction to that of the chains H carrying away the crossrods with the empty hangers. Fig. 4 explains the discharging arrangement for the trays 5 from the oven, when the conveyer taking away the disconnected trays travels in the beginning in the same direction as that in which the chains carrying away the crossrods with the empty hangers, move around 10 the lower part of the discharging sprocket wheel. The latter is represented diagrammatically by O₁ and revolves around its axle o₁. The chains H move in the direction of the arrows, downward at the right hand side 15 of the sprocketwheel where the trays containing the baked articles ready to leave the oven, arrive, and upward at the left hand side where the hangers are empty. The endless conveyer Q for carrying away the trays 20 to be discharged from the oven, is arranged at such a distance underneath the sprocketwheel O₁, that the studs of the trays can not interfere with the empty brackets of the hangers passing by, and stretches far enough 25 to that side of the sprocketwheel O₁, at which the trays traveling downward, arrive, for easily and securely receiving and carrying them away in the direction of the arrow, the brackets of the hangers disconnecting 30 themselves from the studs of the trays by going downward and passing out underneath them. The conveyer Q is worked in the ordinary way by rollers, one of which, K rotated around its axle r, is shown. 35 When the upmost tray A₁, carried by the hangers C₁ of the crossrod D₁ is at the position I, the tray A₂, is at the position II, just settling down on the conveyer Q, while the hangers C₂ suspended from their crossrod 40 D₂ going downward on the sprocketwheel O₁, are disconnecting themselves from the studs B₂ of the tray. At the same time the crossrod D₃ with the empty hangers C₃ arrived at the position III, and the crossrod 45 D₄ with the empty hangers C₄ at the position IV, going upward to be reloaded, and the tray A₃ disconnected from D₃ is on the conveyer Q, taking the baked articles out of the oven, while the tray disconnected 50 from C₄ has already left the oven.

This cycle of operations is continuously repeated.

In order to prevent the brackets of the hangers having just been disconnected from 55 the studs of the trays from interfering with these studs again while both brackets and studs travel in the same direction at the same time, it is necessary for the disconnected trays on the conveyer Q to travel sufficiently quicker than the rods from which the disconnected hangers are suspended.

In the drawing Fig. 4 the relation of the diameter of the roller R to that of the sprocketwheel O₁ is such, that, when the 60 former revolves with about four times the ve-

locity as the latter, the trays on the conveyer Q make in the same interval about double the way as the hangers on the crossbars traveling around the lower part of the sprocketwheel O₁, which increase of speed for the 70 trays to be discharged is quite sufficient for the desired result, as the position of the disconnected tray A₃ on the conveyer Q demonstrates.

I claim:

1. In devices for charging and discharging apparatus of the kind described, the combination with the trays holding the articles to be treated, of studs attached to each end of these trays, of crossrods rotatably mounted at their ends in and connecting two chains traveling through the apparatus in the same direction and at the same speed, of hangers rotatably suspended from these crossrods, and of brackets fixed to these 80 hangers and adapted to receive the studs of the trays, the said crossrods, hangers, brackets and studs being so adapted and arranged that the studs of the trays engage with the brackets of the hangers, when the latter and 90 the crossrods carrying them pass by in an upward direction, and that the studs of the trays disengage from the brackets of the hangers, when the latter and the crossrods carrying them, pass by in a downward direction. 95

2. In devices for charging and discharging apparatus of the kind described, the combination with the trays holding the articles to be treated, of studs attached to each end 100 of the trays, of crossrods rotatably mounted at their ends in and connecting two chains traveling through the apparatus at the same speed and in the same direction, of hangers rotatably suspended from these crossrods, 105 of brackets fixed to the hangers and adapted to receive the studs of the trays, and of a conveyer carrying the trays, if they are to be charged into the apparatus, to a point therein where the brackets of the hangers suspended from the crossrods mounted in the chains passing by the conveyer in an upward direction, engage with the studs fixed to the trays which are thus connected to and carried upward by the chains, and carrying 110 the trays, if they are to be discharged, out of the apparatus, receiving them therein at a point where the said brackets of the hangers suspended from the crossrods mounted in the chains passing by the conveyer in a downward direction, disengage from the studs of the trays, which are thus deposited on and then taken away by the 115 said conveyer.

3. In devices for charging and discharging apparatus of the kind described, the combination with the trays holding the articles to be treated, of studs attached to the trays, of crossrods rotatably mounted in and connecting the chains moving the 120

- trays through the apparatus, of loose wheels rotatably mounted on the said crossrods, of rails supporting these wheels and so arranged in the apparatus as to secure to the 5 chains the right direction of travel and stability, of hangers rotatably suspended from the said crossrods, of brackets fixed to these hangers and adapted to easily engage with and disengage from the studs of the trays, 10 and of conveyers arranged in the apparatus at points where the studs of the trays when on the said conveyers, are bound to engage with the brackets of the hangers passing by in an upward direction, and to disengage 15 from the brackets of the hangers passing by in a downward direction.
4. In devices for charging and discharging apparatus of the kind described, the combination with the trays holding the articles to 20 be treated, of studs attached to each end of the trays, of crossrods rotatably mounted at their ends in and connecting two chains traveling through the apparatus in the same direction and at the same speed, of hangers 25 rotatably suspended from these crossrods, of brackets fixed to the hangers and adapted to engage with and disengage from the studs of the trays, of loose wheels rotatably mounted on the said crossrods between the 30 hangers and the chains, of rails arranged in the apparatus where the chains are running in a more or less horizontal direction, and provided with grooves for the said loose wheels to travel in, of brackets fixed to the 35 frame-work of the apparatus and supporting the said rails, of a conveyer carrying the trays holding the articles to be treated, to a point in the apparatus where the brackets of the hangers suspended from the said 40 crossrods passing by with their chains in an upward direction, engage with the studs of trays which are thus carried upward into the apparatus, and of a conveyer adapted and arranged to remove the trays holding 45 the treated articles from the apparatus, receiving these trays therein at a point where the brackets of the hangers suspended from the said crossrods passing by with their chains in a downward direction, disengage 50 from the studs of the said trays, which are thus deposited on and then taken out of the apparatus by the said conveyer.
5. In devices for charging and discharging apparatus of the kind described, the 55 combination with the trays holding the ar-

ticles to be treated, of two studs attached to each end of these trays, of crossrods—one corresponding to each tray—rotatably mounted at their ends in and connecting the two endless, parallel chains carrying the 60 trays through the apparatus, of hangers—two for each crossrod, respectively for each tray—rotatably suspended from the said crossrods and kept in position thereon by suitable means, and of curved brackets two 65 of which are attached to each hanger, pointing opposite to the ends of the crossrods from which their hanger is suspended, and with their concavity upward, and thus forming seats for the studs fixed to the trays, 70 the said hangers being arranged on each crossrod in such a manner that the trays find ample room between them and can be easily lifted by means of their studs on and off the brackets of the hangers, and 75 that the latter—without fouling anything—carry the trays during their whole circuitous course through the apparatus in an horizontal position.

6. In devices for charging and discharging apparatus of the kind described, the combination with the trays holding the articles to be treated, of studs attached to 80 each end of these trays, of crossrods rotatably mounted at their ends in and connect- 85 ing two parallel chains traveling in the same direction and at the same speed and moving the trays through the apparatus, of hangers rotatably suspended from these crossrods, of brackets fixed to these hangers 90 and so adapted and arranged that they engage with the studs of the trays, thus supporting the latter, and of conveyers carrying the trays holding articles to be treated, into, and the trays holding the treated ar- 95 ticles out of the apparatus, and consisting of two parts, one being an endless-band- 100 conveyer, and the other being composed of loose rollers placed in alinement at a point of the apparatus where the chains with their crossrods and hangers pass by, when the trays are to be seated by their studs on the brackets of the hangers, in an upward direction, and when the trays are to be removed from these seats, in a downward di- 105 rection.
